REPEAT MECHANISM FOR TYPEWRITERS

Filed Jan. 11, 1926

Inventor:
Robert A. Mack
By: *Nicolaus Crane Atty.*

UNITED STATES PATENT OFFICE

ROBERT A. MACK, OF WASHINGTON, DISTRICT OF COLUMBIA, ASSIGNOR TO WOODSTOCK
TYPEWRITER CO., OF WOODSTOCK, ILLINOIS, A CORPORATION OF ILLINOIS

REPEAT MECHANISM FOR TYPEWRITERS

Application filed January 11, 1926. Serial No. 80,395.

This invention relates to means for producing repeated action of a type carrier in a power driven typewriting machine.

The object of the invention is to provide a simple and improved device whereby a particular type carrier may be caused to operate repeatedly without the necessity of repeated depressions of the corresponding key.

The invention is exemplified in the combination and arrangement of parts shown in the accompanying drawing and described in the following specification and it is more particularly pointed out in the appended claims.

15 In the drawing:

Fig. 1 is a vertical sectional view of a portion of a typewriter showing one embodiment of the present invention applied thereto;

20 Fig. 2 is a detail sectional view on line 2—2 of Fig. 1.

The invention is illustrated as applied to the Woodstock "Electrite" typewriter but it will be understood that it is not limited to 25 this particular type of machine.

In the drawing, the numeral 10 designates the frame of a power driven typewriter having a toothed roller 11 journaled in the frame and extending transversely thereof. The 30 roller 11 is continuously driven by any suitable power mechanism, not shown. The typewriter is provided with the usual key levers 12 and type bars 13. Sublevers 14 are connected with the type bars 13 in the usual manner and pivoted on the cross bar 16.

Actuators 17 are pivoted at 18 to the sub-levers 14 and are provided with hooks 19 for engaging the teeth on the power drive 11. A bar 20 is supported on end brackets 21 40 secured to the sides of the frame and carries a plurality of springs 22 which engage extensions 23 on the ends of the actuators 17. These springs 22 normally hold the sub-levers 14 and type bars 13 in retracted position. The key levers 12 are provided with contact fingers 24 which engage lugs 25 on the corresponding actuators 17. When a key lever is depressed the finger 24 will move the hook 19 into engagement with the power 45 drive 11 so that the actuator will be drawn

forwardly and the type bar operated. At the end of its movement, the extension 23 will strike an adjustable stop screw 26 to free the actuator from the power drive and permit the spring 22 to return the parts to 55 their normal position. Each key lever 12 carries a downwardly extending projection 27 to which a shoe 28 is attached. The shoe 28 is arranged to co-operate with interlocking mechanism carried by a cross bar 29 but this mechanism is not a part of the present invention. The mechanism thus far described is similar to that employed by the Woodstock "Electrite" typewriter, described in the application of Otto A. Hokanson, 60 Serial No. 732,615, filed August 11, 1924.

It will be noted from Fig. 2 of the drawing that the shoe 28 comprises a strap or bar of metal bent about the projection 27 and that the lower end of the shoe is angularly bent 65 to form a pointed end as shown at 30. This leaves an open space 31 between the end of the shoe and the lower end of the projection 27. According to the present invention, a tappet 70 in the form of a wire or rod 32 is inserted 75 through this open space and secured in position therein in any suitable way as, for instance, by bending the end about the shoe 27 as shown at 33. The rear end of the wire 32 is bent downwardly and provided with a lateral extension 34 which overlies the extension 23 of the actuator 17. It will be seen that this projection 34 will act in a manner similar to the finger 24 in pressing the hook 19 into engagement with the power drive 11 80 when a key lever is depressed. If the key lever is retained in depressed position, however, the projection 34 will intercept the extension 23 on the return of the actuator to its inoperative position and will hold the actuator down as it is drawn backwardly by the spring 22. This will direct the tooth 19 85 into re-engagement with the drive 11 so that the operation of the actuator and type carrier 13 will be repeated. In this way, the type carrier will be automatically repeatedly operated so long as a key lever is held in depressed position.

It will be apparent that the attachments 32 90 may be readily applied to as many different 100

key levers as desired and may be easily detached any time that it is no longer required. The attachment will not interfere with the usual operation of the typewriter since the movement of the actuator is repeated only when the key lever is held in depressed position. If the key lever is released after it is struck, the typewriter will operate in the usual manner and only a single impression will be made.

10 I claim:

1. In a typewriter, the combination with a type carrier, of a power drive, an actuator for connecting said type carrier with said power drive, a key lever having a socket opening therein, and a tappet arranged to enter said socket opening, said tappet being held in position by said opening to engage said actuator and to direct said actuator into release 15 engagement with said power drive after release therefrom.

2. In a typewriter, the combination with a type carrier, a power drive, an actuator for connecting said type carrier with said power drive, a key lever, an interlocking shoe 25 mounted on said key lever and forming a socket opening therewith, and a repeat tappet engaging said socket opening and held thereby in position to engage said actuator when said key lever is depressed.

3. In a typewriter, the combination with a type carrier, of a power drive for said type carrier, an actuator for connecting said power drive with said type carrier, said actuator 35 having a forward extension thereon, means for disconnecting said actuator from said power drive, a spring for returning said actuator to its initial position, a key lever, a downwardly extending projection on said key lever having a socket opening therein, and a tappet arranged to engage said socket opening and held thereby in position to engage the top of said extension when said key lever is depressed.

40 45 In testimony whereof I have signed my name to this specification on this 31 day of December, A. D. 1925.

ROBERT A. MACK.
